WRENCH

Carl Frederick Carlson, Peoria, Ill.

Application July 25, 1935, Serial No. 33,165

1 Claim. (Cl. 81—176)

The object of the invention is to provide a wrench in which the jaws are relatively movable to provide for adjustment for various size nuts and to accomplish such adjustment by the one hand in which the wrench is carried so that the jaw setting operation may be readily accomplished where the use of two hands is impossible or inconvenient; and to provide a wrench of the kind indicated which is of simple form and susceptible of cheap manufacture.

With this object in view, the invention consists in a construction and combination of parts, of which a preferred embodiment is illustrated in the accompanying drawing, wherein:

15 Figure 1 is a side elevational view of a wrench constructed in accordance with the invention.

Figure 2 is an edge elevational view.

Figure 3 is a sectional view on the plane indicated by the line 3—3 of Figure 2.

20 Figure 4 is a sectional view on the plane indicated by the line 4—4 of Figure 1.

While the invention is shown incorporated in the conventional form of wrench in which the stationary jaw 10 is integral with the combined shank and handle 11, it is applicable to any other form of wrench in which turning movement is employed to adjust the movable jaw 12 toward and away from the stationary jaw. In the illustrated embodiment showing the conventional form of wrench, the shank 11 is provided on the one edge with the rack teeth 14 of the proper inclination to be engaged with the thread of the worm 15, the latter being disposed in an opening in the jaw 12, so as to rotate freely therein, and to this end being carried on a stem 16 arranged parallel with the shank 11, the stem extending through the jaw 12 on opposite sides of the opening to provide journal portions for the stem. The stem is substantially coextensive 35 in length with the combined shank and handle portion 11 and in the handle area passes through a slide 17 which is adapted for movement over the shank 11 throughout the handle area, which

is graduated in fractions of an inch as indicated at 18.

The stem 16 is angularly but not axially movable with respect to the slide 17, said stem having a collar 19 abutting the slide on one end and a ferruled portion 20 of a handle 21 abutting the slide on the opposite end. The handle 21 is of the general form of the conventional screw driver handle and its diameter is greater than the thickness of the shank 11, so that it may be readily grasped by the fingers of the hand in which the handle portion of the shank 11 is carried.

The scale 18 formed on the handle area of the shank 11 provides, in connection with the slide 17, an indicator from which the spacing of the jaws 11 and 12 may be determined.

The wrench when held in the hand may be readily adjusted by manipulation of the fingers on the handle 21, so that in the event the user 20 must employ one hand to hold the work being operated upon, he may make the necessary jaw adjustment readily with the other hand.

The invention having been described, what is claimed as new and useful is:

A wrench comprising fixed and movable jaws, a combined shank and handle member with which the former jaw is fixedly connected and on which the latter is slidably mounted, a rotary member carried by the movable jaw and having positive 30 operative connection with the shank to traverse the latter and effect movement of the jaw along the shank, a stem fixed with respect to said rotary member and paralleling the shank, and a handle carried at the end of the stem adjacent 35 the handle area of the shank, the shank being formed with a scale graduated in linear units and having a slide mounted thereon movable over the scale, the slide being operatively connected with the stem to permit relative angular 40 movement between it and the stem but to preclude relative axial movement between the two.

CARL FREDERICK CARLSON.
